[57] CLAIM

I claim the ornamental design for an ergonomic computer mouse, as shown and described.

DESCRIPTION

FIG. 1 is a top view of an ergonomic computer mouse showing my new design;

FIG. 2 is a bottom view thereof;

FIG. 3 is a rear view thereof;

FIG. 4 is a front view thereof;

FIG. 5 is a left side view thereof; and,

FIG. 6 is a right side view thereof.

The broken line illustration in the drawings disclosure (FIGS. 1, 3-6) is not part of the design sought to be patented.
